UNITED STATES PATENT OFFICE

97,859

DESIGN FOR A TEXTILE FABRIC

John P. Meehan, Los Angeles, Calif.

Application March 18, 1935, Serial No. 55,910

Term of patent 3½ years

To all whom it may concern:

Be it known that I, John P. Meehan, a citizen of the United States, residing in the city and county of Los Angeles, State of California, have invented a new, original, and ornamental Design for Textile Fabric, of which the following is a specification, reference being had to the annexed drawing, forming a part thereof.

The figure is a view of a fabric showing my new design.

I claim:

The ornamental design for a textile fabric, as shown.

JOHN P. MEEHAN.
